US0D1024669S

(12) **United States Design Patent** (10) **Patent No.:** **US D1,024,669 S**
(45) **Date of Patent:** **** Apr. 30, 2024**

(54) **COOKWARE**

(71) Applicant: **Lagom Kitchen Co.**, Culver City, CA (US)

(72) Inventors: **Amir Tehrani**, Los Angeles, CA (US); **Zachary Rosner**, Los Angeles, CA (US); **Stuart Harvey Lee**, Forest Hills, NY (US); **Jochen Schaepers**, New York, NY (US)

(73) Assignee: **Lagom Kitchen Co.**, Culver City, CA (US)

(**) Term: **15 Years**

(21) Appl. No.: **29/886,908**

(22) Filed: **Mar. 15, 2023**

Related U.S. Application Data

(60) Continuation of application No. 29/825,171, filed on Jan. 28, 2022, now Pat. No. Des. 988,072, which is a continuation of application No. 29/800,803, filed on Jul. 23, 2021, now Pat. No. Des. 972,881, which is a division of application No. 29/748,445, filed on Aug. (Continued)

Primary Examiner — Messina L Smith

(74) *Attorney, Agent, or Firm* — Banner & Witcoff, Ltd.

(57) **CLAIM**

The ornamental design for a cookware, as shown and described.

DESCRIPTION

FIG. 1 is a top, front perspective view of a cookware showing our new design;

FIG. 2 is a bottom, rear perspective view thereof;

FIG. 3 is a right side view thereof;

FIG. 4 is a left view thereof;

FIG. 5 is a rear view thereof;

FIG. 6 is a top view thereof; and,

FIG. 7 is a bottom view thereof.

The broken lines immediately adjacent to the shaded area define the bounds of the claimed design and form no part thereof. The broken lines depicting the remainder of the cookware form no part of the claimed design.

1 Claim, 3 Drawing Sheets

Related U.S. Application Data

28, 2020, now Pat. No. Des. 929,798, which is a continuation-in-part of application No. 29/699,401, filed on Jul. 25, 2019, now Pat. No. Des. 916,547.

(58) Field of Classification Search

CPC 37/01; A47J 37/10; A47J 37/101; A47J 37/105; A47J 33/00

See application file for complete search history.
